(57) CLAIM

We claim the ornamental design for a building automation device, as shown and described.

DESCRIPTION

FIG. 1 is a bottom, front, left perspective view of an embodiment of the claimed design;
FIG. 2 is a top, rear, left perspective view thereof;
FIG. 3 is a front view thereof;
FIG. 4 is a rear view thereof;
FIG. 5 is a cross-section view thereof along line 5-5 in FIG. 4;
FIG. 6 is a top view thereof;
FIG. 7 is a bottom view thereof;
FIG. 8 is a left side view thereof;
FIG. 9 is a right side view thereof;
FIG. 10 is a bottom, front, left perspective view of an embodiment of the claimed design;
FIG. 11 is a top, rear, left perspective view thereof;
FIG. 12 is a front view thereof;
FIG. 13 is a rear view thereof;
FIG. 14 is a cross-section view thereof along line 14-14 in FIG. 3;
FIG. 15 is a top view thereof;
FIG. 16 is a bottom view thereof;
FIG. 17 is a left side view thereof;

FIG. 18 is a right side view thereof;
FIG. 19 is a bottom, front, left perspective view of an embodiment of the claimed design;
FIG. 20 is a top, rear, left perspective view thereof;
FIG. 21 is a front view thereof;
FIG. 22 is a rear view thereof;
FIG. 23 is a cross-section view thereof along line 23-23 in FIG. 22;
FIG. 24 is a top view thereof;
FIG. 25 is a bottom view thereof;
FIG. 26 is a left side view thereof; and,
FIG. 27 is a right side view thereof.

The broken lines depict portions of building automation device that form no part the claimed design. The building automation device is shown broken away in FIGS. 19-27 of the drawing to indicate indeterminate length, it being understood that it has a uniform shape and appearance through its length.

Building automation devices include, but are not limited to, thermostats, sensors, lighting controls, building controls, and heating, ventilation, air-conditioning, and refrigeration equipment controls.
